UNITED STATES PATENT OFFICE

2,416,763

CONVEYING MEANS

Charles B. Lynch, Cleveland, Ohio, assignor, by
mesne assignments, to The Foundry Equipment
Company, Cleveland, Ohio, a corporation
of Ohio

Application July 12, 1944, Serial No. 544,597

9 Claims. (Cl. 198—219)

1

This invention relates to conveying means and is particularly adapted to use in furnaces and similar locations where articles of considerable weight must be moved mechanically at varying rates of speed.

An object of the invention is to provide an improved conveying mechanism in which the speed of motion of the articles carried may be accurately controlled.

Another object is to provide an improved conveying mechanism which will be simple in construction.

Another object is to provide an improved conveying mechanism which will be capable of withstanding long and hard usage.

Another object is to provide an improved conveying mechanism in which parts will be protected against heat.

Another object is to provide an improved conveying mechanism which will require relatively little power in its operation.

Another object is to provide an improved conveying mechanism which may be simply and automatically controlled.

Other objects will hereinafter appear.

The invention will be better understood from the description of one practical embodiment thereof, illustrated in the accompanying drawings, in which:

Figure 1 is a fragmentary vertical sectional view of a portion of a heat treating furnace provided with a conveying mechanism embodying my invention;

Figure 2 is a plan sectional view of the parts shown in Figure 1, parts having been omitted for the sake of clarity;

Figure 3 is a fragmentary transverse sectional view taken on the line III—III of Figure 2, and showing only the stationary supporting portion of the structure;

Figure 4 is a fragmentary view, to an enlarged scale, similar to Figure 3, but showing both the stationary and movable supporting parts of the conveyor;

Figure 5 is a fragmentary longitudinal sectional view of the end of the conveyor mechanism remote from that shown in Figure 1, to an enlarged scale; and,

Figure 6 is a cross sectional view taken on the line VI—VI of Figure 5.

The furnace illustrated is defined by side walls 1 and 2 and ends 3, and, it will be understood, is provided with a top and suitable heating means, which, however, constitute no part of the present

2

invention and are, therefore, omitted for the sake of clarity.

The furnace comprises a generally elongated rectangular chamber having openings at opposite ends, into one of which the work or articles to be heat treated may be introduced and through the other of which such articles may be discharged and delivered.

The conveyor mechanism moves these articles in a step-by-step manner, and spaced apart as desired, through the furnace within which they are, of course, exposed to the heat required for the process to which they are being subjected.

The conveyor illustrated is made in three identical sections indicated at A, B, and C in Figure 2 which may be operated independently or jointly, so that if the furnace is being used for the treatment of small articles each section may handle an independent series of such articles, while if the articles are larger, two, or even all three, of the conveyor sections may be operated together, the articles extending across each of these sections and being partly supported by each of them.

Inasmuch as the sections are identical, the description of the operating mechanism of one section will suffice for the others.

Each conveyor section consists of two sets of longitudinally extending rail-like supports, the members of the two sets being alternately arranged, and one set being permanently fixed, while the other is moveable relative thereto, both vertically and longitudinally.

The stationary supports are shown as a series of rail-like metal members including I beams 4, while the movable rails consist of a similar series of longitudinally extending members comprising I beams 5.

The stationary rails 4 are carried by a plurality of stationary transversely extending beams 6, which extend horizontally across a pit 7 which passes beneath the furnace proper and extends for a slight distance at each end thereof to receive mechanisms for receiving and discharging articles and for operating the conveyor.

To raise the stationary rails 4 to the proper heights within the furnace, there are interposed between them and stationary beams 6, vertical struts 8 carrying at their upper ends short transverse beams 9, on the tops of which are a plurality of stools 10 on which the rails 4 rest.

The struts 8, beams 9 and stools 10 are all conveniently formed of rolled metal sections, such as channel shaped sections, and secured together

as by welding or riveting, being reinforced and stiffened by gussets 11 and angles 12.

The upper flanges of rails 4 and 5 are each provided with small transverse spacers 13, such as short pieces of half rounded bar stock welded upon the upper surfaces of these flanges to prevent articles carried thereby from rolling into contact with each other.

The ends of the transverse beams 6 are supported upon ledges of recesses 14, formed in the lining of the pit 7, which lining is preferably composed of masonry, concrete, or other suitable material and which is also formed with upwardly extending pillar-like supports 15 for the mechanisms which carry the movable rails.

Upon the supports 15 under each conveyor section is a series of supporting rollers 17, each carried by a shaft 18 journaled in a supporting bracket shown as consisting of two angles 19 secured as by welding to a plate 20, which rests upon the upper surface of support 15.

Upon these rollers are supported two horizontal parallel channels 21 extending lengthwise of the furnace which constitute, with their connecting parts (to be hereinafter described), a longitudinally reciprocable frame carrying the movable rails 5.

Engaging the upper flanges of these channels are rollers 22, similar to rollers 17, which hold the channels against undesired upward movement, these rollers being mounted on shafts 23, carried by brackets consisting of angles 24, secured to plates 25, which in turn are secured to and suspended from the underside of transverse beams 26, supported, as are beams 6, but below some of the latter, in recesses formed in the masonry side walls of the pit 7.

The channels 21 are connected at one end by a transverse channel shaped yoke 27, reinforced by a section I beam 28, as illustrated in Figure 5, and at spaced points along their length are connected by box-like frames consisting of vertical side plates 29 to which are secured, as by angles 30, horizontal top and bottom transversely extending short channel sections 31 and 32, respectively, these parts also being connected together and to the channels 21 most conveniently by welding.

The top and bottom channel sections 31 and 32 of each box frame are provided with bearings or bushings 33 in vertical alignment, through which may reciprocate vertically a supporting post or rod 34. This post has secured to it a collar 35, held against longitudinal movement relative the post by a pin or rivet 36, and is provided with sidewise extending trunnions 37.

Upon these trunnions are pivoted the upper ends of two links 38, the lower ends of which are pivoted upon a pin 39 fixed in a yoke 40.

Also pivoted on the pin 39 are two depending links 41, the lower ends of which are pivoted by pins 42 to the box frame, the pins extending through angle 30 and side plates 29 and also through blocks 43 secured to the upper surface of the channel 32.

Upon the upper end of rod 34 is a supporting beam or arm 44, having on its upper surface short channel shaped stools 45, which, in turn, support the movable rails.

These rails have cap spacers 46, similar to the caps 13 of the stationary rails.

The links 40 span the supporting posts 34, so that they have a limited horizontal motion with respect to these posts, which motion moves the pivot pins 39 toward and away from the posts so

that the links 38 and 41 constitute a toggle action, raising or lowering the post depending upon the motion of the yokes 40.

The yokes 40 of successive box frame stations 5 are connected by rods 46, threaded into the ends of these yokes.

At the station of the post at one end of the conveyor, shown in Figure 5, the yoke has been made in two parts, each being bifurcated and the furcations of each overlapping and being pivoted upon the same pin 39.

One of these parts 47 is connected to the end of the last bar 48, as are the various yokes 40 of the series, while the other part 48 is threaded to the end of a piston rod 49 carrying in its other end a piston 49a reciprocable in a cylinder 50. The cylinder is mounted upon trunnions 51 journaled in the side channels 21.

It will be apparent that hydraulic pressure may be admitted to either end of cylinder 50, and will reciprocate the piston therein, which reciprocation is transmitted through piston rod 49 to the various rods 46, causing the yokes 40 and 41 to move in unison and, through the toggle action of the links 38 and 41, raise and lower the posts 34 also in unison.

A bracket 52 is secured to the outer side of yoke 27, and to this is pivoted a fitting 53 carried by the end of a piston rod 54. This, in turn, is connected to a piston 55, reciprocable in a cylinder 56 stationarily mounted upon the concrete foundation of the pit. Hydraulic pressure on either side of the piston 55 reciprocates the frames consisting of the channels 21 and associated parts horizontally.

The bottom of the furnace 57 closely embraces the stationary struts 8, while through it are formed slots 58 in which the post 34 may move both vertically and horizontally to permit the full movement of the parts as the frames 21 are reciprocated.

Surrounding each post 34 and resting upon the top of the floor 57 is a cover plate 59 having a perforation which closely fits the periphery of its post, but which is just loose enough to permit the post to move up and down through the perforation without lifting the plate above the floor.

These plates 59 overlie the slots 58 and are of sufficient extent to effectively cover and close these at all positions of the post 34, so that all the parts below the floor 57 are effectively protected from radiant heat passing downwardly from the furnace, and also from heated currents of air.

If desired, Z-shaped guides may be secured to the top of the floor 57 to keep the plates 59 from twisting on the posts and to prevent their upward movement.

Thus the space within the pit 7 is maintained very much cooler than is that within the furnace. Ordinarily, its temperature is not much above that of the atmospheric outside, so that the rollers 17 and 22, the bearings, the horizontal frame, together with all associated parts, such as the toggle links 38 and 41 and the hydraulic actuated means, are all maintained at moderate temperatures and protected against warpage, sticking, and other deleterious effects to which conveyors within a furnace proper have heretofore been subjected.

The continuous open space within the pit from end to end of the furnace may, if the furnace be installed where extreme conditions exist, be fur-

ther cooled by blowing cool air therethrough, but ordinarily this will not be found necessary.

The outer ends of the stationary beams 4 are supported by transverse arms or beams 60 carried by stationary posts 61 which, in turn, are supported upon transverse beams 62.

As shown in Figure 1, a stop may be secured to the ends of these beams consisting of upwardly extending posts 63 fastened to the beams and also to angles 64, and carrying transversely extending channel sections 65 which will prevent articles from being shoved off the end of the stationary supporting frame by the action of the movable rails.

It will be understood that the valve mechanisms which control the flow of fluid to the cylinders 50 and 56 may be automatically actuated, and that the actuation of these valves may be such as to vary the length of stroke of the pistons 49a and 55 as desired, and to interpose any desired time intervals in any part of the cycle of operation.

When the device is put into operation, a valve is opened to admit fluid to the left hand end of the cylinder 50 (with the parts in the positions they occupy in Figure 5).

This moves the piston to the right and pulls yokes 40 also to the right, moving the links 38 and 41 to substantially vertical position, and raising the movable rails 5 so that they project above stationary rails 4 as shown in dot-and-dash lines in Figure 4.

This motion, of course, picks up the objects upon the carrier, without translating them.

The mechanical advantage of the toggle mechanism increases as the articles are raised, and their weight, when fully elevated, is transmitted through compression of the links, so that little power is required to hold them up.

At the upper end of this lifting step a valve mechanism is actuated for admitting fluid to the left hand end of cylinder 56. The motion produced by this fluid, moving piston 55 to the right, pulls the entire carriage including the supported articles to the right, while the articles are still elevated by the projecting movable rails 5.

When the carriage has reached any desired position, a valve mechanism may reverse the flow of fluid into cylinder 50, and introduce the pressure into its right hand end.

This will return piston 49a to the left, breaking the toggles and lowering the posts 34 to retract the movable rails below the level of the tops of the stationary rails, or into the positions where they are shown by the solid lines of Figure 4.

As the movable rails pass below the level of the stationary rails, the articles are deposited upon the tops of stationary rails and left there until the movable rails are again elevated.

Upon the lowering of posts 34, the valve controlling the admission of fluid to cylinder 56 may be reversed, so that pressure is now supplied to the right hand of this cylinder, which moves the entire carriage to the left to its starting position.

Valve mechanisms are illustrated rather diagrammatically in Figure 5.

This figure shows a valve 66 mounted upon cylinder 50 and having an actuating arm 67. This arm lies in the path of two adjustable dogs 68 carried by an extended arm 69 fixed to a stationary plate 70 which connects brackets 19 and 24. The lugs may be adjusted along the arm as by set screws 71, to adjust the length of stroke permitted before actuation of the valve 66.

It will be apparent that as the arm 67 encounters one or the other of the lugs 68, this arm is swung to reverse the flow of fluid to cylinder 50, and thus to move the rods or posts 34 in a direction opposite that in which they have last moved.

Secured to one head of the cylinder 50 is a long spring arm 71, having an elongated slot or eye 72 adjacent its end remote from the cylinder.

10 In this slot slides one end of link 73 secured to an actuating arm 74 of a valve mechanism 75 associated with cylinders 56.

This arm 74 may be provided with a dash pot mechanism 76 with an adjustable port 77 to serve as a time controlling factor.

15 Thus, it will be seen that when posts 34 are lowered by piston 49a moving to the left (as seen in Figure 5) cylinder 50 is rocked in a counter-clockwise direction and the end of lever 71 is raised. This raises the end of arm 74, which actuates valve 75 to admit fluid into the right hand end of cylinder 56, and so moves the channels 21 and their associated parts to the left.

20 When cylinder 50 swings in a clockwise direction, in raising or extending posts 34, the right hand end of lever 71 is urged downwardly, to move arm 74 downwardly and thus reverse the supply of fluid and direct it into the left hand end of cylinder 56.

25 30 The speed with which arm 74 and the end of spring 71 can move down is, however, controlled by the dash pot 76 which may be set to provide any desired amount of delay in the opening of valve 75. Flexure of spring 71 maintains the downward pressure on arm 74 and the dash pot during this delay period.

35 Thus, the adjustment of dogs 68 limits the length of the horizontal stroke of the conveyor apparatus, while the adjustment of dash pot 76 by means of its adjustable outlet 77 controls the time consumed per cycle of the apparatus.

40 45 Of course, the time taken by an object in passing along the conveyor from end to end will be a function of a number of cycles of operation performed by the movable rails for any given period of time, and also of the distance travelled per cycle, and so may be easily predetermined by two simple adjustments.

45 50 It will be noted that while large and heavy objects may easily be supported on the conveyor bars, the points of support are spaced apart at all times, and that ample space for the circulation of heated gases and other heating media underneath as well as at the sides and top of the articles is provided.

I claim:

55 1. Conveyor mechanism comprising a series of stationary rails, a series of movable rails, stationary supports for said series of stationary rails, a horizontally translatable framework, vertical guideways carried thereby, a plurality of vertically movable supports carried in said guideways and supporting said series of movable rails, links pivoted to the vertically movable supports, links each having one end pivoted in fixed relation to said framework and the other end pivoted to one end of one of the first mentioned links, a connector attached to the joints between the ends of the pairs of links and moving means connected to said connector.

60 65 70 75 2. Conveyor mechanism comprising a series of stationary rails, a series of movable rails, stationary supports for said series of stationary rails, a horizontally translatable framework, vertical guideways carried thereby, a plurality of verti-

cally movable supports carried in said guideways and supporting said series of movable rails, elevating mechanism associated with said supports within the framework, a generally horizontal baffle between the framework and the rails having openings through which the supports may reciprocate vertically and in which they may move horizontally, and closures for said openings have openings closely fitting the supports and permitting vertical movement of the supports without movement of the closures, the closures moving with the supports upon horizontal movement of the framework.

3. Conveyor mechanism comprising a series of stationary rails, a series of movable rails, stationary supports for said series of stationary rails, a horizontally translatable framework, vertical guideways carried thereby, a plurality of vertically movable supports carried in said guideways and by them guided to be translatable only in a vertical direction relative the framework, elevating means carried by the framework and connected to said supports, and baffle means including parts closely surrounding said supports through which the supports may move freely when moved by said elevating means and which move with the supports upon motion of the framework.

4. Conveyor mechanism comprising a series of stationary rails, a series of movable rails, stationary supports for said series of stationary rails, horizontally translatable framework, vertical guideways carried thereby, a plurality of supports carried in said guideways and supporting said series of movable rails, links pivoted to said guideways, links pivoted to the vertical movable supports and to the first mentioned links, a connector pivoted to the pivotal joint between the ends of the pairs of links, and moving means connected to said connector.

5. Conveyor mechanism comprising a series of stationary rails, a series of movable rails, stationary supports for said series of stationary rails, horizontally translatable framework, vertical guideways carried thereby, a plurality of supports carried in said guideways and supporting said series of movable rails, links pivoted to said guideways, links pivoted to the vertical movable supports and to the first mentioned links, a connector pivoted to the pivotal joint between the ends of the pairs of links, and moving means connected to said connector carried by said framework, and moving means connected to the framework.

6. Conveyor mechanism comprising a series of rails supported at a fixed elevation, a series of vertically movable rails, vertically movable supports carrying the second mentioned series of rails, guides for said supports, links pivoted to said supports, links pivoted to said guides, pivotal connections between the ends of said links, a connector pivotally connected to the connections between the pairs of links, and moving means connected to said connector.

7. Conveyor mechanism comprising a series of rails supported at a fixed elevation, a series of

vertically movable rails, vertically movable supports carrying the second mentioned series of rails, guides for said supports, links pivoted to said supports, links pivoted to said guides, pivotal connections between the ends of said links, a connector pivotally connected to the connections between the pairs of links, and moving means connected to said connector, stop means limiting motion of the links in one direction to a point where the pivotal connections of each series are in substantially vertical alignment.

8. Conveyor mechanism comprising a series of stationary rails, a series of movable rails, fixed supports for the said first mentioned rails, a horizontally arranged carriage, horizontally aligned bearings upon which said carriage may reciprocate, means for reciprocating said carriage, a plurality of vertical guides carried by the said carriage, upwardly extending supporting posts substantially vertical reciprocable in said guides, a connector extending lengthwise of the carriage and including a plurality of yokes surrounding said supporting posts, a connector moving means carried by the carriage, each supporting yoke having pivotally connected to it the ends of two links, the opposite ends of one of said links being pivotally connected to the carriage, the opposite end of the other link being pivotally connected with the supporting post, the supporting posts carrying the movable series of rails.

9. Conveyor mechanism comprising a series of stationary rails, a series of movable rails, fixed supports for the said first mentioned rails, a horizontally arranged carriage, horizontally aligned bearings upon which said carriage may reciprocate, hydraulic means for reciprocating said carriage, a plurality of vertical guides carried by the said carriage, upwardly extending supporting posts substantially vertical reciprocable in said guides, a connector extending lengthwise of the carriage and including a plurality of yokes surrounding said supporting posts, a connector moving means carried by the carriage, each supporting yoke having pivotally connected to it the ends of two links, the opposite ends of one of said links being pivotally connected to the carriage, the opposite end of the other link being pivotally connected with the supporting post, the supporting posts carrying the movable series of rails, valve means controlling said hydraulic means, and adjustable means controlling said valve.
